UNITED STATES PATENT OFFICE

GORDON AUGUSTUS WEARHAM, OF LONDON, ENGLAND

DISPLAY APPARATUS AND METHOD OF OPERATING THE SAME

Application filed May 21, 1929, Serial No. 364,855, and in Great Britain May 23, 1928.

This invention relates to apparatus for use in displaying matter of various kinds, such as advertisements, picture, notices, articles of merchandise and the like (hereinafter referred to generally as "display matter") of the type wherein a container that contains a liquid screen, such as an opaque milk-like liquid screen, has a wall, e. g. a glass wall, constituting a window through which the 10 said screen is visible, the thickness of which screen is varied so as to change the appearance of the apparatus, as by rendering display matter associated with the container visible or invisible or changing its appearance 15 when viewed through the window. One example of apparatus of this type is described and illustrated in the co-pending patent application Serial No. 364,854, filed 21st May, 1929.

20 The present invention has for one of its objects to provide that when such apparatus is mounted on a movable support, such as a motor-driven vehicle, or is mounted to swing on a fixed or movable support, it shall be actuated automatically by the changes in the 25 rate of its speed of movement.

According to an important feature of the invention, a method of operating display apparatus of the type described consists in varying the thickness of the liquid screen, for example reducing it to zero, in the container under the action of the inertia of a 30 movable mass, such as a weight, associated with the container.

35 According to another important feature of the invention, there is provided apparatus of the type described, wherein the thickness of the liquid screen is varied, for example reduced to zero, under the influence of the inertia of a movable mass, such as a weight, that is associated with the container and is arranged to move bodily in relation thereto or a part thereof, and displace liquid in the container in order to change the appearance 40 of the apparatus.

45 According to another feature of the invention, the movable mass is displaceable in the liquid in the container, for example is resiliently supported therein, and is arranged, when moving under the action of its inertia,

to move the display matter, which may be carried by the movable mass, towards and away from the window.

According to yet another feature of the invention, the wall constituting the window or the opposed wall of the container is flexible and the other is rigid, and the movable mass, such as a weight, is carried directly by the flexible wall, for example at the middle thereof.

According to a further feature of the invention, the movable mass is in the form of, or constitutes, a piston movable freely in a cylinder, and a conduit containing a fluid, such as air, operatively connects the cylinder with 65 the interior of the container or with an actuating chamber associated therewith.

Other features of the invention will be described hereinafter and pointed out in the 70 claims.

Several forms of apparatus according to the invention and adapted for carrying the described method into practice are diagrammatically illustrated, by way of example, in the accompanying drawing, wherein:—

Figure 1 is a diagrammatic vertical transverse section taken through one form of display sign according to the invention, and

Figures 2, 3 and 4 are like views of modified forms.

Like reference characters designate like parts in the several views.

Referring first to Figure 1, the display sign consists of a container comprising a frame 10 of rectangular or other convenient shape having at the front a transparent or translucent wall 11, for example of glass, constituting a window, and at the rear an opposed wall 12 which may be transparent, translucent or opaque, and an opaque liquid 85 completely or partly filling the space 13 between these opposed walls. A movable mass 14 in the form of a plate-shaped weight, e. g. of metal, is suspended as by springs 15 or by a flexible diaphragm or in any other convenient manner in the liquid so as to be free to move to and fro between the middle portion 90 of the two opposed walls 11, 12. This weight 14 carries on its face towards the window the display matter 16, which may be in the form 95 100

of yielding material, such as rubber, shaped to form letters for example, and adapted to bed tightly against the window 11. Alternatively, the display matter may be painted or otherwise applied to the weight, for example it may be embossed, engraved, printed, stamped, stencilled or photographed thereon. A mount 17, of cardboard or other convenient material, for example paint, may be arranged around the marginal portion of the window 11, either inside the latter as shown, or outside, in order to obscure from view the liquid surrounding the display matter and the suspension means of the weight 14.

When such a display sign is mounted on a movable support, such as a motor-driven vehicle, facing in the direction of travel of the vehicle or in the opposite direction, and changes in the rate of speed of travel occur, the weight with the display matter will be moved, under the action of inertia, towards and away from the window, whereby the display matter will become alternately visible and invisible owing to the thickness of the liquid screen between the window and the display matter being varied and at times reduced to zero.

If desired the rear wall 12 of the display sign may also be transparent or translucent, and display matter may be carried on both sides of the movable weight 14 so as to provide a double-acting sign. Also the weight 14 itself may be transparent, e. g. of glass, and then the display matter may be on its rear face. The opaque liquid may be milk-like, black or coloured any desired tint. Alternatively, a coloured or tinted transparent liquid may be used, in which case its colour may contrast with, for example be complementary to, the colour of the display matter.

One or both of the said opposed walls of the sign may be flexible, and a movable mass may be mounted on either or both of such flexible walls. Figure 2 shows such a construction of display sign, wherein the rear wall is constituted by a flexible diaphragm 20 of celluloid, metal or other convenient material, whereof the marginal portion is preferably corrugated, as at 21, to enhance its flexibility. The weight 14 may be mounted in any convenient position on this diaphragm either inside or outside the container. When outside the same the display matter may be on the inner face of the diaphragm as shown at 16, but when the diaphragm is transparent the display matter may be at any convenient position outside the container so as to be visible through that portion of the window 11 behind which the thickness of the liquid screen is varied or reduced to zero by the action of the inertia of the weight 14. When the diaphragm 20 is of india-rubber or like material and the middle portion approaches the window 11, the other portion of the dia-

phragm will bulge outwards to accommodate the liquid displaced from in front of the weight. If desired, however, a storage compartment 22 that opens into the space 16 may be provided at any convenient part of the container for accommodating the displaced liquid. This compartment 22 may have a filling plug 23 and may contain a source of light 24, such as an electric lamp, arranged to illuminate the liquid, or both the liquid and the display matter, in the space 13. When the diaphragm 20 is transparent or translucent, a source of light, such as electric lamps, may be arranged behind the container, as indicated at 25.

The whole or part of the wall 20, or display matter on the inner face thereof, may be coated with a self-luminous composition.

In order to prevent the liquid of the sign from freezing during cold weather, it may contain an ingredient, such as glycerine, for lowering the freezing point.

Instead of placing the weight 14 shown in Figure 1 opposite the aperture 26 in the mount 17, it may be arranged behind the mount nearer the top of the sign, and it may have a downwardly-directed extension in the form of a flap that carries the display matter opposite the aperture 26 so as to be visible through the latter.

If desired, the signs described above may be mounted to swing to and fro, like a pendulum, on a fixed or movable support so that the thickness of the liquid screen will be varied at the end of each swing.

Figures 3 and 4 show modified constructions of display signs wherein the inertia of a weight acts not directly on the liquid screen, but through the medium of fluid pressure produced under the influence of the inertia of the weight. In Figure 3 a closed actuating chamber designated generally 30 and containing either a gas or liquid is arranged behind the diaphragm 20, and has a rear flexible wall 31 carrying a massive body 14 in the form of a metal weight. The diaphragm 20 which may have the display matter 16 moulded on it is common to the container of the liquid screen and to the actuating chamber 30.

In Figure 4 the movable mass is a body of mercury 40 constituting a piston movable freely in a cylinder 41 in the form of a U-tube, and a conduit 42 which may contain gas or a liquid serves to connect the cylinder 41 with the upper part of a storage chamber 43 that opens into the bottom of the space 13 for liquid. In this construction a back board 44, or a third sheet of transparent, translucent or opaque material may be arranged behind the diaphragm 20, either spaced away therefrom, as shown, or close to it, a vent-hole 45 being provided to connect the space 46 between the two walls 20, 44 with the atmosphere so as to al-

low the diaphragm 20 to flex freely under the action of fluid pressure produced by the movement of the mercury 40.

Instead of the above described arrangements of the display matter, such matter, for example in the form of a stencil or transparency, may be wholly or in part provided on the window 11 at the front or rear thereof. If it is on the front of the window the front face of the weight 14 in the container, or the front face of the rear wall 20 of the container, if the weight is outside the latter, will preferably be coloured or it may also carry some display matter. Also when the liquid is transparent or translucent and tinted, the front face of the weight 14 or wall 20 may be coloured, and the various colours may contrast with, or be complementary to, one another.

Any of the signs described above may be provided in front of the window with a coloured screen of transparent material, such as celluloid, as shown at 28 in Figures 1 and 4. Such a screen may have a coating of paint 29 on its marginal portion to serve as a mount instead of or as well as the mount 17.

Various modifications may be made in the details of construction described above without departing from the scope of the invention as defined by the claims.

I claim.

1. A method of operating display apparatus wherein a container that contains a liquid screen has a wall constituting a window through which the screen is visible, consisting in varying the thickness of the liquid screen in the container under the action of the inertia of a movable mass associated with the container.

2. A method of operating display apparatus wherein a container that contains a liquid screen has a wall constituting a window through which the screen is visible, consisting in varying the thickness of the liquid screen in the container under the action of fluid pressure produced under the influence of the inertia of a movable mass that is associated with the apparatus, so as to change the appearance of display matter.

3. A method of operating display apparatus wherein a container has two opposed walls with a liquid screen between them, one of which walls constitutes a window through which the screen is visible, and at least one of which walls is flexible, consisting in flexing a flexible wall of the container towards and away from its opposed wall under the action of fluid pressure produced under the influence of the inertia of a movable mass that is associated with the apparatus, and thereby varying the thickness of the liquid screen so as to change the appearance of the apparatus.

4. Display apparatus comprising a con-

tainer having one wall constituting a window, and liquid constituting a screen situated in the container so as to be visible through the window, in combination with a movable mass that is associated with the container and is arranged to move bodily under the influence of inertia in relation to a part of the container and thereby vary the thickness of the liquid screen.

5. Display apparatus comprising a container having two opposed walls and a liquid screen between them, one of which walls constitutes a window, and at least one of which walls is flexible and movable towards and away from the other wall, in combination with a movable mass that is movable bodily under the influence of inertia carried by the flexible wall.

6. In display apparatus of the character described, a container having two opposed walls spaced apart, a liquid screen between said walls, one of which walls constitutes a window, and one of which walls is flexible and movable towards and away from the other wall, a weight movable under the influence of inertia carried by the flexible wall, and a storage compartment for liquid opening into the space between said walls.

7. Display apparatus comprising in combination a container whereof one wall constitutes a window, and an opposed wall is movable towards and away therefrom, a liquid screen in the container between the opposed walls, an actuating chamber operable by fluid pressure arranged to move said movable wall towards and away from the window, and a mass movable under the influence of inertia arranged to vary the fluid pressure in said actuating chamber.

8. Display apparatus comprising in combination a container whereof one wall constitutes a window, and an opposed wall is movable towards and away therefrom, a liquid screen between the opposed walls, an actuating chamber situated at the side of said opposed wall remote from the window and arranged to move said opposed wall towards and away from the window, which actuating chamber has a flexible wall, and a weight movable under the influence of inertia carried by the latter wall.

9. Display apparatus comprising in combination a container having one wall constituting a window, liquid constituting a screen situated in the container so as to be visible through the window, and a movable mass that is displaceable in the liquid under the influence of inertia towards and away from the window, and is so associated with display matter that the latter is movable with said mass.

10. Display apparatus comprising in combination a container having two opposed walls and a liquid screen between them, one of which walls constitutes a window and at

least one of which walls is movable towards and away from the other wall, a movable mass that is associated with the container and is arranged to move bodily under the influence of inertia in relation to the container and thereby vary the thickness of the liquid screen, both of which walls at opposite sides of said screen are translucent.

11. In display apparatus of the character described, a container having two opposed walls spaced apart, a liquid screen between said walls, one of which walls has a marginal portion thereof corrugated so as to render it movable towards and away from the opposed wall, and a movable mass that is associated with the container and is arranged to move bodily under the influence of inertia in relation to the container and thereby flex said corrugated wall and move it towards and away from the opposed wall.

12. Display apparatus comprising in combination a container having one wall constituting a window, liquid constituting a screen situated in the container so as to be visible through the window, a movable mass that is associated with the container and is arranged to move bodily under the influence of inertia in relation to the container and thereby vary the thickness of the liquid screen, and illuminating means situated in said container and arranged to illuminate said screen.

13. Display apparatus comprising in combination a container having one wall constituting a window, liquid constituting a screen situated in the container so as to be visible through the window, a movable mass that is associated with the container and is arranged to move bodily under the influence of inertia in relation to the container and thereby vary the thickness of the liquid screen, at least a part of the inner face of the wall of the container opposed to the window being coated with a self-luminous composition.

14. Display apparatus comprising in combination a container having one wall constituting a window, liquid that contains an ingredient for lowering the freezing point thereof constituting a screen situated in the container so as to be visible through the window, and a movable mass that is associated with the container and is arranged to move bodily under the influence of inertia in relation to the container and thereby vary the thickness of the liquid screen.

15. Display apparatus comprising in combination a container having one wall constituting a window, and liquid constituting a screen situated in the container so as to be visible through the window, a movable mass that is associated with the container and is arranged to move bodily under the influence of inertia in relation to the container and thereby vary the thickness of the liquid

screen, which mass has associated with it display matter that is movable with it and is visible through said window.

In testimony whereof I affix my signature
GORDON AUGUSTUS WEARHAM.
